DESIGN FOR A CLOSURE FOR CONTAINERS OR SIMILAR ARTICLE

Harold L. Van Doren and Charles K. Ellsworth,
Toledo, Ohio, assignors to Wheeling Steel Cor-
poration, Wheeling, W. Va., a corporation of
Delaware

Application February 23, 1935, Serial No. 55,589

Term of patent 14 years

To all whom it may concern:

Be it known that we, Harold L. Van Doren and Charles K. Ellsworth, both citizens of the United States, residing at Toledo, Ohio, have invented a new, original, and ornamental Design for a Closure for Containers or Similar Article, of which the following is a specification, reference being had to the accompanying drawing, forming part thereof.

In the drawing

Figure 1 is a top plan view of a closure for containers; and

Figure 2 is a perspective view of the closure for containers shown in Figure 1.

We claim:

The ornamental design for a closure for containers or similar article substantially as shown.

HAROLD L. VAN DOREN.

CHARLES K. ELLSWORTH.
